TRAWLING MOTOR

Leard E. Lisk, P.O. Box 5126, Greensboro, N.C.

Filed Aug. 12, 1963, Ser. No. 76,193

Term of patent 14 years

(Cl. D71—1)

FIG. 1 is a perspective view of a trawling motor showing my new design;

FIG. 2 is an enlarged fragmentary side elevational view of the motor portion;

FIG. 3 is an enlarged fragmentary side elevational view of the clamp portion;

FIG. 4 is an enlarged fragmentary rear elevational view of the motor portion; and

FIG. 5 is an enlarged fragmentary sectional view taken above the clamp portion.

I claim:

The ornamental design for a trawling motor, as shown.
